SUPPLY MEANS FOR WASHING MACHINES

Lucien Pierce, Malden, Mass.

Original application March 18, 1938, Serial No. 196,689. Divided and this application August 30, 1939, Serial No. 292,670

2 Claims. (Cl. 68—17)

This invention relates to means for supplying laundering materials such as soap, blue, sour, etc. to washing machines together with an inflow of water to form successive pools for the various steps of a washing cycle. In my copending application Serial No. 196,689, filed March 18, 1938, now Patent Number 2,206,330, issued July 2, 1940, of which this application is a division, a completely automatic apparatus is described and illustrated for operating a washing machine through all the details of an entire cycle. Valves are operated by the control mechanism at predetermined intervals to introduce successive pools of water into the machine and to supply measured quantities of laundering materials with the water as required for the several steps in the cycle. It is desirable that such laundering materials be mingled with the water supply stream prior to entering into the machine, so that they will be quickly and thoroughly distributed through the respective pools in the machine. According to the present invention, apparatus is provided for ensuring proper introduction of the various laundering materials into the machine.

For a more complete understanding of the invention, reference may be had to the following description thereof, and to drawings of which:

Figure 1 is an end elevation of a washing machine showing apparatus embodying the invention.

Figure 2 is a section on the line 2—2 of Figure 1.

Figure 3 is a section on the line 3—3 of Figure 1.

Figure 4 is a section on the line 4—4 of Figure 3.

Figure 5 is a section on the line 5—5 of Figure 4.

In Figure 1 a washing machine such as is used in steam laundries is conventionally indicated at 21. Water for the various washings and rinsing steps of a cycle is supplied to the machine through a pair of valves 120 for hot and cold water. These valves are mounted on a convenient supporting frame 20 which also supports a set of small tanks 294 from which laundering materials are released by control means not shown herein but fully described and illustrated in my said application, such laundering materials flowing into a trough 300 below the tanks.

The water supply which passes through the valve 120 for the washing machine enters a vertical up-take 320 and passes into a horizontal delivery pipe 322 through a constriction in the pipe

formed by an apertured diaphragm 324. The pipe 322 leads into the washing machine casing 21. A nozzle 326 is connected through a suitable trap 328 to the trough 300 and projects centrally through the aperture in the diaphragm 324. 5 The trap prevents the escape of steam or moist vapor from the washing machine into the trough 300. As indicated in Figure 5, the diaphragm 324 consists of a pair of overlapping plates which slide in grooves and are adjustable toward and from each other by means of adjusting screws 329 so as to vary the clearance between the edges of the opening and the nozzle 326. The plates of the diaphragm 324 are initially adjusted when a machine is installed, in order to adapt the opening in the diaphragm to the local water pressure. No further adjustment is then required if pressure conditions in the supply system remain the same. The arrangement of the nozzle 326 results in a hollow cylinder of water flowing past 10 the end of the nozzle when washing materials are being supplied therethrough from the trough 300. Soap is supplied to the trough 300 from a suitable source (not shown herein) through an aperture 236. In order to carry the soap effectively to the nozzle 326, a pipe 330 is led from the up-take 320 to a nozzle 332 in the trough 300 directed toward the trap 328. A branch pipe 334 is also connected to the pipe 330 and leads to a spray pipe 336 arranged along the upper edges of the trough 300 in the vicinity of the aperture 236. Another branch 338 of the pipe 330 leads to an outlet 340 at the upper end of the trough 300 so as to wash down the liquid materials which are discharged into the trough from the tank 294. Since the pipe 330 leads from the up-take 320, it is evident that the water supplied therethrough for flushing the trough 300 flows only when the valve 120 is open. The timing mechanism on the machine is arranged so that the washing materials, such as soap and the like, are discharged into the trough 300 only during such times as water is being supplied to the machine.

It is evident that various modifications and changes may be made in the embodiment of the invention herein illustrated and described without departing from the spirit or scope thereof as defined in the following claims.

I claim:

1. In a washing machine having a casing, a water supply duct leading into said casing, an adjustable constriction in said duct, a nozzle projecting through said constriction, and means for

50

55

supplying laundering materials to said nozzle for discharge therethrough into said duct.

2. In a washing machine, a supply duct for water, a trough for laundering materials, a pipe leading from said trough and projecting into said duct, the discharge end of said pipe being directed to discharge said laundering materials in

the same direction as the flow of water in the duct at the discharge end of the pipe, said discharge end also being spaced from the walls of the duct whereby the stream issuing from the pipe is surrounded by the stream of water flowing past said orifice. 5

LUCIEN PIERCE.
